UNITED STATES PATENT OFFICE.

JOHN T. GILMER, OF FLORALA, ALABAMA.

MUFFLER.

1,018,044.

Specification of Letters Patent. Patented Feb. 20, 1912.

Application filed June 26, 1911. Serial No. 635,495.

To all whom it may concern:

Be it known that I, JOHN T. GILMER, a citizen of the United States, residing at Florala, in the county of Covington and 5 State of Alabama, have invented certain new and useful Improvements in Mufflers, of which the following is a specification.

This invention relates to mufflers for overcoming and destroying the noise produced 10 by the exhaust from explosive engines, and is intended more particularly for use upon automobiles, although its usefulness is not confined to that field.

The object of the invention is to provide 15 a muffler which may be produced at a slight cost and by the use of which the exhaust will be muffled without creating appreciable back pressure upon the engine.

A further object of the invention is to 20 provide a muffler of simple construction which may be readily applied to the exhaust pipe of any engine and readily adjusted to the condition of any particular case.

These stated objects, and such other incidental objects as will appear as the description of the invention proceeds, are attained in the use of such a device as is illustrated in the accompanying drawings and herein-after fully described, the novel features of 30 the invention being particularly pointed out in the appended claims.

In the drawings, which illustrate the preferred embodiment of my invention, Figure 1 is a longitudinal sectional elevation of a 35 muffler containing my improvements; Fig. 2 is an end elevation; Fig. 3 is a longitudinal sectional elevation showing a modification.

In carrying out my invention, I secure to 40 the end of the exhaust pipe 1 a T-coupling 2 from the opposite sides of which extend tubes 3 having their outer ends closed by caps 4¹. The tubes 3 project from the coupling laterally with respect to the exhaust 45 pipe and are then carried rearwardly and outwardly in parallel planes, as shown. The dimensions of the tubes and the coupling are capable of variations within certain limits, but for the best results the combined diameters of the two tubes should be 50 greater than the diameter of the exhaust pipe 1 so that the exhaust gases passing into these tubes will be permitted to expand and their pressure consequently reduced. Ex- 55 tending inwardly from the opposed surfaces of these muffler tubes 3 are a series of

branches or nozzles 4 which have their terminals arranged directly opposite each other, said branches or nozzles being arranged in pairs, as will be readily understood from the drawings. To the ends of the opposed members of each pair of nozzles, I secure cups or spreaders 5 which are threaded upon the extremity of the nozzles so that they may be adjusted to and from 60 each other to vary the size of the opening or space left between their edges and thereby control the escape of the expanded gases.

In the drawings I have illustrated three pairs of nozzles or outlets 4 with their attached cups or spreaders, but it will be readily understood that the particular number is immaterial and a greater or lesser number may be employed according to the 70 requirements of any particular engine.

A housing 6 is arranged around the muffler tubes 3, their outlets 4, and the spreaders attached thereto, and this housing may be of any suitable material which will possess the requisite durability and strength 80 without excessive weight, sheet metal being desirable and preferably used. This housing is in the form of a hood inclosing but spaced from the muffler tubes and having its front closed end 7 fitted upon the exhaust pipe 1 and secured thereon by a nut 8 bearing against the said end or head 7 and clamping the same against an annular shoulder on the T-coupling 2, as shown and as will be readily understood. A cover or 90 cap plate 9 is secured to the caps 4¹ on the outer or rear ends of the muffler tubes 3 and extends between the said tubes. This cover or cap plate prevents too rapid exhaust or discharge of the gases and is provided with 95 a series of longitudinal narrow slits 10 through which the exhaust may escape.

The plate 9 may be of such dimensions as to entirely close the outer end of the housing but better results are obtained when the edge 100 of the plate is out of contact with the end of the housing whereby a narrow open space 11 is provided to permit a more extended escape of the exhaust gases.

The construction and arrangement of the 105 several parts of my muffler being thus made known it is thought the operation and advantages of the same will be readily understood and appreciated.

The exhaust gases from the engine pass 110 through the exhaust pipe 1 into the coupling 2 and are there divided into two

streams which pass into the muffler tubes 3 connected with the said coupling. As the capacity of these tubes is greater than the capacity of the exhaust pipe the gases are 5 permitted to expand therein so as to relieve their tension and in order to accentuate the decrease in their pressure and to further attenuate the same I provide air inlet tubes 12 which extend from the front end or head 10 of the housing 6 into the respective muffler tubes 3, as clearly shown. As the expanded gases flow toward the outer or rear ends of the muffler tubes portions thereof will flow into and through the outlets or nozzles 4 15 and, escaping from the ends thereof, will be broken up by the contact with the gases escaping from the opposed nozzles or outlets and will escape from between the cups or spreaders 5 in thin streams having but little 20 tension or pressure. As the volume of gases within the muffler tubes is successively decreased by the loss of portions thereof through the nozzles or outlets 4, the pressure within the said tubes will be correspondingly reduced toward the outer or rear 25 ends thereof with the result that the gases escaping through the last nozzles will have practically no pressure. The gases escaping from between the opposed cups or 30 spreaders will be received within the interior of the housing 6 and will consequently be permitted to expand to a great degree therein and will finally escape from the said housing through the narrow slots 10 and 35 the space 11. As the escaping gas is divided into a number of fine streams in passing through said space and slots, the sudden exhaust of a large volume of gas into the atmosphere and the consequent formation 40 of a vacuum adjacent the discharging point is entirely overcome so that the noise usually attendant upon the exhaust of an explosive engine is eliminated.

When the muffler is applied to an automobile the travel of the vehicle will cause air to pass into and through the tubes 12 to commingle with the gases in the muffler tubes 3 and thereby weaken the gases so that the explosive force of the same will be destroyed.

When the device is used on a stationary engine the initial expansion of the gases within the muffler tubes will create a sufficient partial vacuum to draw in air through 55 said tubes 12. These air tubes furthermore, serve as vents so that should the parts be improperly adjusted and the muffler fail to provide for the proper and sufficient expansion of the exhaust gases, the resulting 60 back pressure of the gases will be relieved through these tubes and will not be transmitted to the engine. The several spreaders or cups are capable of adjustment upon the nozzles 4 so that varying degrees of expansion 65 may be permitted between the spread-

ers of each pair and the muffler consequently easily and readily adjusted to effectively reduce the pressure of the exhaust of any engine to which it may be applied.

The several parts of my muffler may be 70 constructed of inexpensive material and consequently the muffler may be produced at a slight cost.

As there is no complicated arrangement 75 of parts, repairs may be easily made if necessary and the muffler may be easily cleaned whenever it is desired to do so.

In the modification shown in Fig. 3, a Y-coupling 13 is substituted for the T-coupling 2 shown in Fig. 1, thereby providing a more direct passage to the muffler tubes and reducing the liability of back pressure. On the rear ends of the coupling are external spaced lugs 14 having inclined or cam faces and on the ends of the muffler tubes are swiveled collars 15 provided with internal lugs 16. The muffler tubes are alined with the ends of the coupling, the lugs on the collars passing through the spaces between the lugs on the coupling after which the 90 collars are rotated about the muffler tubes so that the lugs on the collars will ride upon the inclined faces of the lugs on the coupling and thereby firmly secure the tubes in place. The front end or head of the housing is in 95 the form of a separate plate or cap 17 having an annular flange 18 at its outer edge to fit around the end of the cylinder 19 forming the body of the housing. The cap plate 9 is provided with spaced extensions 100 or tongues 20 which engage over the rear end of the cylinder so that when the said plate is secured to the ends of the muffler tubes, the cylinder will be clamped against the front plate 17. Minute openings 21 105 may be provided in the muffler tubes near the rear ends thereof to permit the escape of the gases and prevent accumulation of the gases to form cushions in the tubes and, to further weaken the gases before their final 110 discharge into the atmosphere, air intake tubes 22 may be secured in the side of the housing and terminate in the expansion chamber formed by the housing around the muffler tubes.

Having thus described my invention, what I claim and desire to secure by Letters Patent is:—

1. A muffler comprising a pair of tubular members adapted to be secured to the exhaust pipe of an engine, and a series of nozzles extending toward each other from the opposed surfaces of said tubular members.

2. A muffler comprising a pair of tubular members having closed outer ends and adapted to be secured to the exhaust pipe of an engine, outlet nozzles projecting toward each other from said tubular members, and spreaders on the ends of said nozzles.

3. A muffler comprising a pair of tubular members having closed outer ends and adapted to be secured to the exhaust pipe of an engine, outlet nozzles projecting toward each other from said tubular members, and spreaders adjustably fitted on the ends of the nozzles.

4. A muffler comprising a housing secured upon the end of an engine exhaust pipe, means leading from the said exhaust pipe within the housing to permit expansion of the exhaust gases, and means communicating with said first mentioned means and discharging into the housing to successively permit increased expansion.

5. A muffler comprising expansion members adapted to be secured to the exhaust pipe of an engine, outlets arranged successively along the said members, and air

intakes leading from the outside air 20 through the front ends of said members.

6. A muffler comprising a housing adapted to be secured upon the exhaust pipe of an engine, a pair of tubular members within the housing having their front ends secured to the said exhaust pipe and their outer ends closed, opposed nozzles projecting from the said tubular members, and a cap plate secured to and extending between the closed outer ends of said members and 30 provided with a plurality of attenuated escape openings.

In testimony whereof I affix my signature, in presence of two witnesses.

JOHN T. GILMER.
